UNITED STATES PATENT OFFICE.

GODFRIED LAUBE, OF HURON, SOUTH DAKOTA, ASSIGNOR OF ONE-HALF TO
JOSEPH HYMANS, OF CHICAGO, ILLINOIS.

WASHING-MACHINE.

SPECIFICATION forming part of Letters Patent No. 514,854, dated February 13, 1894.

Application filed July 1, 1893. Serial No. 479,875. (No model.)

To all whom it may concern:

Be it known that I, GODFRIED LAUBE, a citizen of the United States of America, residing at Huron, in the county of Beadle and State of 5 South Dakota, have invented certain new and useful Improvements in Washing-Machines, of which the following is a specification, reference being had to the accompanying drawings.

This invention has relation generally to 10 washing machines and particularly to that class thereof known as rocking body machines, or operating on the oscillating principle; the clothes to be washed are placed in a suitable receptacle capable of being rocked 15 back and forth, whereby the air and water within the receptacle, are forced through the clothes in alternately opposite directions without rubbing the same more than is absolutely necessary for the thorough cleaning of the 20 clothes.

The objects of my invention are, first, to provide a machine of this class, in which the clothes receptacle is constructed with a series of wings set at right angles to the interior 25 walls or opposite ends of the machine, said wings having corrugations and then bent downwardly at an angle approximately at forty-five degrees, said wings forming a series of pockets or chambers, adapted to operate as 30 hereinafter described; secondly, to provide a series of ribs on the interior sides of the receptacle, for the purpose of slightly rubbing the clothes; thirdly, to provide a removable weight under the clothes receptacle, by which 35 means a uniform and steady motion is attained when the machine is in operation, and furthermore it will serve to retain it in its normal position when not in use; fourthly, to provide a washing machine with a wringer mounted 40 on the top thereof and suitable means for substantially retaining the machine in its normal position when said wringer is used.

The final object is to construct a machine that will be strong, durable and very easy to 45 operate, furthermore to prevent the tearing or bundling of the clothes.

With these various objects in view my invention consists in the details of construction, and combination or arrangement of parts hereinafter described and specifically pointed out 50 in the claims.

Referring to the accompanying drawings forming a part of this specification wherein like letters of reference indicate similar parts throughout the several views, Figure 1. is a 55 vertical longitudinal section through the center of the machine. Fig. 2. is a transverse section through the center of the machine. Fig. 3. is a side view of the machine showing the movable support or standard arranged at 60 the side of the machine resting on and against the lower portion of the frame work and in dotted lines placed in its proper position when the machine is in operation. Fig. 4. is a detail view of the air chambers. 65

In the drawings—A, represents the frame work or standards between which the clothes receptacle is secured, B, the clothes receptacle, C, C, C, the air chambers, D, D, D, the wings forming said chambers, said wings being bent at E, and having corrugations e, e, 70 e, e, &c.

F, F, F, represent the ribs arranged in the interior sides of the receptacle.

G, G, represent the rods extending from the 75 lower four corners of the machine, supporting a standard or upright H, which passes through the center of the weight I. J, the spout or outlet arranged in any suitable manner on the bottom of the receptacle provided with the 80 plug or cap j, for same. K, the movable arm or support arranged on the exterior of the receptacle at the bottom near the end of the machine, said support being hinged at k, and retained in position by a clasp L. M, the 85 wringer, mounted on top of the machine, N, the handle on opposite sides of the washer.

The operation of the machine is as follows: The machine is filled partly with water, soap suds and the clothes to be washed; by oscillating the machine the water and goods come in contact with and are forced against the ends of the machine; the water washes up under the wings and by this means forces the air out through the clothes, the ribs or ridges 90 on the side acting in the capacity of a wash board of the ordinary construction; the main or middle side walls of the machine are left smooth in order not to obstruct the free passage of the water and clothes when operating 95 the machine, and allowing full sweep for the accumulation of force with which the con-

tents strike the ends and thereby thoroughly cleanse the clothes; when this has been accomplished the machine is drained and the hinged support let down to bear against the frame work, thus giving the machine substantial support for the purpose of turning the clothes through the wringer.

5 The frame work may be made in any suitable manner and the machine constructed of wood, sheet metal, or both.

10 It will be obvious that various changes may be made in the detail construction of this machine without departing from the general idea involved.

15 Having fully described my invention, what I claim as new, and desire to secure by Letters Patent, is—

1. A washing machine mounted on a movable frame, the combination of the corrugated 20 wings set at right angles, bent and extending

downwardly at an approximate angle of forty-five degrees, said wings forming air chambers arranged at the ends of the clothes receptacle, a series of ribs or ridges set at different angles on the sides of said receptacle, substantially as described.

2. In a washing machine, the combination of the corrugated wings arranged at right angles and extending downwardly, said wings forming air chambers at the ends of the clothes receptacle, a series of ribs set at opposite angles on the sides of said clothes receptacle and forming a free space between the series of ribs, substantially as described.

25 In testimony whereof I affix my signature in presence of two witnesses.

30 GODFRIED LAUBE.
